UNITED STATES PATENT OFFICE

154,298

DESIGN FOR A CALENDAR STAND OR SIMILAR ARTICLE

Carlyle N. Montanye, Baltimore, Md.

Application February 18, 1948, Serial No. 144,576

Term of patent 14 years

(Cl. D74—5)

To all whom it may concern:

Be it known that I, Carlyle N. Montanye, a citizen of the United States, residing at Baltimore, and State of Maryland, have invented a new, original, and ornamental Design for Calendar Stand or Similar Article, of which the following is a specification, reference being had to the accompanying drawing, forming part thereof.

In the drawing, Figure 1 is a front elevation of a calendar stand or similar article, showing my new design.

Fig. 2 is a top plan view and Fig. 3 is an end view thereof. The end not shown is substantially the same as the one shown.

I claim:

The ornamental design for a calendar stand or similar article, as shown and described.

CARLYLE N. MONTANYE.
